UNITED STATES PATENT OFFICE.

JOHN C. LACKNER, OF NEW YORK, N. Y.

DESIGN FOR A PAPER CASE FOR CONFECTIONERS' USE.

SPECIFICATION forming part of Design No. 12,404, dated August 9, 1881.

Application filed June 25, 1881. Term of patent 7 years.

To all whom it may concern:

Be it known that I, JOHN C. LACKNER, of the city, county, and State of New York, have invented a new and original Design for Paper Cases for Confectioners' Use, of which the following is a specification.

In the accompanying drawing a perspective view of my newly-designed paper case for confectioners' use is shown. It consists of an elliptical or like paper case, A, pointed toward the rear and open on top, so that the cake, cream, &c., can be placed into it. A paper wing, B, is attached to each side, and a neck,

C, made of kinked paper, with a head, D, is attached to the front of the case, so that the whole will resemble a swan.

Having thus described my invention, I claim as new and desire to secure by Design Patent—

The design for paper cases for confectioners' use herein shown and described, the same consisting of a rounded casing, A, provided with wings B, a neck, C, and a head, D.

JOHN C. LACKNER.
